CLAIM

The ornamental design for a fingernail dryer, as shown and described.

DESCRIPTION

FIG. 1 is a top perspective view of a fingernail dryer;

FIG. 2 is a top plan view thereof;

FIG. 3 is a bottom plan view thereof;

FIG. 4 is a bottom plan view in the closed position thereof;

FIG. 5 is a front elevational view thereof;

FIG. 6 is a rear elevational view thereof;

FIG. 7 is a right side elevational view thereof;

FIG. 8 is a left side elevational view thereof; and,

FIG. 9 is a bottom perspective view thereof.

The broken lines shown in the drawing views are included for the purpose of showing environmental structure that forms no part of the claimed design.
